**HYDRAULIC PULL-DOWN MECHANISM FOR
ROTARY DRILLING RIGS**
Wilbur M. Stevenson, 2675 S. Jasmine,
Arapahoe County, Colo.
Filed Apr. 13, 1964, Ser. No. 359,363
10 Claims. (Cl. 173—147)

This invention relates to rotary drilling equipment and more specifically, to an improved hydraulic pull-down mechanism therefor that provides "free-spudding" while the drill pipe and bit remain attached to the "kelly."

When drilling a well with rotary drilling equipment, a string of drill pipe with a bit fastened to the lower extremity thereof is attached to and suspended from the lower end of a so-called "kelly-bar" or rod. This kelly bar has exterior grooves or ways adapted to slidably receive keys or the equivalent carried in a drive bushing turned by the rotating mechanism of the drilling unit. From time-to-time during the drilling operation it becomes desirable or necessary to supplement the drilling pressure and this is accomplished by the use of a pull-down mechanism which forces the bit into the ground. Devices for this purpose are well known in the art, some of them being of the hydraulic type while others are mechanical.

There is, however, another operation that must be performed from time-to-time with a drilling rig that is incompatible with the prior art hydraulic pull-down mechanisms and that is "spudding" where the drill pipe and bit are raised up and allowed to drop freely back into the hole. There are a number of applications for spudding such as, for example, to fracture down-hole obstructions, to rapidly displace well fluids with the drill pipe acting as a piston so that such fluids are forced toward the surface. Regardless of the particular end result to be achieved, spudding is a useful operation supplementing the ordinary rotary drilling action that should be made available to the driller when it is possible to do so.

Unfortunately, however, spudding operations are exceedingly difficult and time-consuming to perform on rotary drilling rigs equipped with the known hydraulic pull-down mechanisms. The reason is that the pull-down apparatus is connected to the rotary drilling apparatus and prevents the free-falling action of the pipe and bit which are essential to the spudding operation. The only solution, therefore, with the prior art equipment is to completely disconnect the pulldown mechanism from the kelly so that the hoisting winch can raise the drill pipe and release it for a free drop into the hole. This is no simple task and is to be avoided whenever possible.

It has now been found in accordance with the teaching of the present invention with a novel and improved hydraulic pull-down mechanism for rotary drilling rigs can, in fact, be made that will provide for "free spudding" while remaining connected to the drilling apparatus. This desirable end is accomplished by the simple, but obvious, expedient of leaving the head or running block of the pull-down mechanism disconnected from the hydraulic servo-motor that pushes on same to impart additional down-hole pressure on the bit. In other words, with the piston retracted in its cylinder, the head or running block of the pull-down apparatus runs up and down with the kelly as the latter is raised and dropped but said block has little or no effect on the free-spudding action of the

2

bit and drill pipe. Conversely, it is only when the piston is extended that the pull-down apparatus becomes effective to impart a down-hole pressure on the bit. In one embodiment of the invention it is necessary to provide a counterweight assembly to counterbalance the running block and keep the lines tight when spudding while in the other embodiment, gravity alone accomplishes this end.

It is, therefore, the principal object of the present invention to provide a novel and improved hydraulic pull-down apparatus for rotary drilling rigs.

A second objective is the provision of a device of the class aforementioned that permits "free spudding" without being disconnected from the kelly and associated rotating elements.

Another object of the invention herein claimed is to provide a hydraulic pull-down device that necessitates no sacrifice in the supplementary down-hole pressure it is capable of producing in order to accommodate free spudding.

Still another objective is to provide a novel disconnected head or running block that becomes operatively associated with the drive piston only during the work stroke thereof.

An additional objective achieved by the invention herein disclosed and claimed is the provision of the pull-down equipped with means for accomplishing free spudding that does not interfere with insertion and removal of the drill string or other necessary operations thereon.

Further objects are to provide a rotary drilling apparatus and hydraulic pull-down that is simple, inexpensive, efficient, versatile, rugged, easy to service, compact and powerful.

Other objects will be in part apparent and in part pointed out specifically hereinafter in connection with the description of the drawings that follows, and in which:

FIGURE 1 is a fragmentary side elevation showing a wheel-mounted rotary drilling rig equipped with the preferred embodiment of the hydraulic pull-down mechanism of the present invention, portions of the mast having been broken away to reveal the kelly;

FIGURE 2 is a rear elevation of the apparatus shown in FIGURE 1;

FIGURE 3 is an enlarged fragmentary view showing the upper end of the mast that forms the track in which the kelly rides with particular emphasis on the by-pass into which the kelly retracts so as to not obstruct the rod string;

FIGURE 4 is an enlarged fragmentary section taken along line 4—4 of FIGURE 2;

FIGURE 5 is a fragmentary side elevation similar to FIGURE 1 but showing another embodiment of the invention, once again portions of the mast having been shown broken away to reveal the elements hidden thereby;

FIGURE 6 is a rear elevation similar to FIGURE 2 except showing the embodiment of FIGURE 5;

FIGURE 7 is an enlarged fragmentary diametrical section showing one form of travelling head and cylinder that can be used with either of the previously illustrated embodiments; and,

FIGURE 8 is an enlarged fragmentary diametrical section showing second travelling head and cylinder ar-

angement usable with either of the previous embodiments.

Referring now to the drawings for a detailed description of the present invention and, initially, to FIGURES 1, 2, 5 and 6 for this purpose, the apparatus is seen to include a wheel-supported frame 10 upon the bed 12 of which is mounted a winch 14, a mast or derrick 16 and a powered rotating mechanism that has been designated broadly by reference numeral 18. The aforementioned elements find their mechanical and functional counterparts in most of the prior art rotary drilling rigs with the exception of the mast which has been modified to accept the hydraulic pull-down mechanism that comprises the novel feature hereof and which has been referred to broadly by reference numeral 20.

The rotating mechanism 18 includes among other elements a drive bushing 22 which receives a kelly rod 24 so as to form a driving connection therewith while permitting the latter to slide freely up and down therein. Such an operative connection is generally accomplished by means of interlocking splines or the like (not shown) on the mating surfaces of the rod and bushing. A plurality of tubular drill pipe sections (not shown) are suspended from the lower end of the kelly rod and the drill pipe carries a bit on its lower end which bores the hole. Drilling fluids are circulated through the hollow drill pipe string to remove cuttings and perform other operations on the subsurface structures.

The upper extremity of the kelly rod 24 is mounted in a swivel fitting 26 that is raised and lowered up and down the mast by means of the winch 14 and a cable 28 reeved over one or more pulleys 30 journaled for rotation in the top of the mast. The mast or derrick 24, of course, supports the weight of the drill string and cooperates with the winch to raise and lower the latter so that drill pipe sections can be added and removed therefrom.

Next with reference to the first six figures of the drawings, it can be seen that the vertical excursions of the drill string and kelly rod are guided by the rear spaced parallel uprights 32 of the mast which are channel-shaped in the particular form shown to produce tracks within which the trunnions 34 (FIGURE 4) on the outboard ends of the swivel mount 36 ride. In certain instances it becomes necessary to disconnect the rod string from the kelly and move the latter together with the swivel and its mount on one side in order to clear the top of the mast over the bore and in axial alignment therewith. This is accomplished by means of an offset 38 provided in the upper reaches of the track formed by uprights 32. As best seen in FIGURE 3, the offset comprises nothing more than an angularly intersecting track section 40 that merges into an inset parallel section 32, the latter cooperating to deflect the swivel mount 36 forwardly into the dotted line position shown in FIGURES 1 and 5.

The above described apparatus is, except for minor differences, common to both the principal embodiment of the rotary drilling apparatus shown in FIGURES 1 and 2 as well as the modified embodiment of FIGURES 5 and 6. No attempt has been made to illustrate these elements in detail as they are common to most all rotary drilling rigs of the wheel-mounted variety and are significant only in that they provide the structural environment upon which the pull-down mechanism acts. In fact, these same elements may, and do, take many different forms in commercially available drilling rigs, the ones shown being merely representative thereof.

The pull-down mechanism of the present invention in which the novelty resides is presented herein as taking two basically different forms, the first and preferred one being exemplified in FIGURES 1 and 2 wherein the travelling head extends upwardly, and the second shown in FIGURES 5 and 6 where the travelling head extends downwardly. Both of these embodiments are further modifi-

able to utilize either the hydraulic servo-motor arrangement of FIGURE 7 or of FIGURE 8.

Thus, with specific reference to FIGURES 1 and 2, the principal embodiment of the hydraulic pull-down mechanism 20 of the present invention will now be described in detail. A pair of outwardly-opening channel-shaped tracks 44 are mounted on the frame bed 12 so as to extend upwardly therefrom in spaced parallel relation to one another adjacent the front uprights 46 of the mast to which these tracks or rails are welded or otherwise connected for support. The travelling head or running block 48 of the pull-down apparatus has trunnions 50 journaled thereon which ride in these tracks, the trunnions being most clearly revealed in FIGURE 8. The travelling block, therefore, is free to run up and down the mast guided by the aforementioned tracks and in position in front of the kelly, swivel and mounting for the latter. Journaled for rotation within the running block 48 are a pair of sheaves 52 mounted on opposite ends of a common shaft 54. A pair of fixed-length cables 56 are reeved over sheaves 52 with one end dead-ended on the mast as indicated by reference numeral 58 while the opposite end is similarly dead-ended at the swivel mount as shown at 60.

The remainder of the pull-down mechanism comprises a hydraulic cylinder 62 mounted within the mast structure near the upper extremity thereof in inverted position and an extendable piston 64 with a piston rod 66 secured thereto adapted to engage the running block or travelling head 48 forcing the latter down the mast. A source of hydraulic fluid and a pump (not shown) supply fluid under pressure to the hydraulic cylinder in a manner to either extend or retract the piston rod as will be described presently in connection with FIGURES 7 and 8. Thus, it will be apparent that the introduction of fluid under pressure on top of the piston 64 will extend the travelling head forcing the kelly down the mast and supplementing the pressure on the bit.

In the other embodiment, namely, that of FIGURES 5 and 6, these same elements of the pull-down assembly just described in connection with FIGURES 1 and 2 are present, however, they are arranged right-side-up rather than upside-down. For instance, the hydraulic cylinder 62 is now mounted in the lower end of the mast structure with the piston rod 66 emerging from the top. The tracks 44 are the same and the travelling head 48m runs up and down the mast above the cylinder. The travelling head is slightly modified as shown in that it is considerably smaller so as to clear the swivel assembly when in retracted position at the top of the mast. Obviously, the aforementioned differences in size of the travelling head are functions of the mast dimensions and can, for this reason, vary considerably from those illustrated.

Other elements are necessary in the FIGURES 5 and 6 modification that were not needed in the one previously described. For instance, to exert a downward pull on the rod string, a set of fixed pulleys or sheaves 68 must be provided at the base of the mast under which the slightly longer cables 56m must be reeved before being dead-ended at the swivel. Thus, an upward extension of the piston rod 66 will raise the travelling block and pull-down, as before, on the drill string.

As will be explained in detail presently, feature of the present pull-down mechanism that permits "free-spudding" is that the piston rod 66 is disconnected from either the piston or the travelling head so that the latter remains free to move up and down with the piston fully retracted within the cylinder. Now, in the principal version of FIGURES 1 and 2, the weight of the travelling block 48 will cause it to extend and keep the lines 56 tight even though the piston remains retracted, however, in the present modification, the lines 56m will go slack with the piston retracted when the kelly rod moves down unless the travelling head 48m can be raised to take-up

this slack. For this reason the FIGURES 5 and 6 modification is equipped with a counterbalance assembly that has been designated in a general way by reference numeral 70 and which includes a cable 72 attached atop the travelling block that is reeved over a fixed sheave 74 in the top of the mast and thence down to a counterweight 76 which counterbalances the weight of the travelling block 48m, cables 56m and piston rod 66 if the latter is connected to said travelling block rather than the piston. Obviously, this counterbalance assembly will function to raise the travelling head and take out all slack in the cables when the kelly and rod string are allowed to drop freely back down the hole as is done when "free spudding."

Finally, with reference to FIGURES 7 and 8, the two different versions of the hydraulic servo motor assembly have been illustrated, either of which can be used interchangeably on either of the pull-down mechanisms previously described. In both units, the cylinder 62 is essentially the same having conduits 78 and 80 communicating both ends thereof through which fluid may either be introduced or withdrawn. Appropriate valving (not shown) is used to control and reverse the direction of fluid flow thus making the piston 64 "double-acting" in accordance with hydraulic principles well known to the art. The pistons 64 are, likewise, the same in both versions and constitute nothing novel as many different types of hydraulic cylinder pistons will function as well and for the same purpose.

As for the travelling blocks 48a and 48b, both include a box-like frame 82 carrying ball-bearing journals 84 that support shaft 54 for rotation. The sheaves 52 are conventional and fixedly attached to the shaft ends. The differences in these travelling blocks 48a and 48b are in their manner of making operative connection with the piston rod 66. In the FIGURE 7 version the piston rod 66a is permanently and securely attached to the travelling block as by welding so that the piston-rod-block assembly moves as a unit. For this reason the frame 82 is provided with permanent connecting means 86 adapted for attachment to the piston rod. On the other hand, the FIGURE 8 version has box-like travelling head frame 48b equipped with a recessed socket 88 in the wall thereof facing the piston rod 66b, the free end of the latter having a concave shape 90 adapted to fit the aforementioned recess.

The FIGURE 8 version is the simpler of the two and the piston rod 66b is attached to the piston in the usual manner but is disconnected from the travelling head. Thus, with the piston retracted, the rod 66b is retracted also and only the head 48b is free to move by itself in response to reciprocation of the kelly. There remains, of course, the operative association between the head 48b and rod 66b when the piston is being extended to exert positive downward pressure on the rod string.

In the FIGURE 7 version, because the rod 66a is attached to the travelling head 48a it must be detached from the piston 64 if the desired free-spudding is to be available. This is accomplished by the simple expedient of making the piston rod in two telescoping parts, the inner one 92 being connected to the head and freely slideable inside the outer part 94 which is connected to the piston and moves up and down in the cylinder therewith. Both versions, of course, allow the travelling head to move independent of the piston when the latter is retracted.

Having thus described the several useful and novel features of the hydraulic pull-down mechanism of the present invention, it will be seen that the many worthwhile objectives for which it was designed have been achieved. Although but a few specific embodiments of the invention have been illustrated and set forth in detail, I realize that certain other changes and modifications may well occur to those skilled in the art within the broad

teaching hereof, hence, it is my intention that the scope of protection afforded hereby shall be limited only insofar as said limitations are specifically set forth in the appended claims.

5. What is claimed is:
1. In a rotary drilling device of the type having an upstanding mast, drill pipe supporting means adapted to transmit rotational movement to a string of drill pipe suspended therefrom, drive means connected to the drill pipe supporting means operative upon actuation to rotate same, swivel means connected to the mast for vertical movement and connectable to the drill pipe supporting means for raising and lowering the drill pipe while it rotates, and winch means connected to the swivel means operative upon actuation to raise and lower same, the improved mechanism for supplementing the downward force exerted on the drill pipe string which comprises: cable means connecting the swivel means to a fixed support, a running pulley block in rolling engagement with the cable means intermediate the ends thereof operative to exert a downward pull upon the swivel means when a force is applied against said running block in a direction selected to foreshorten the segment of said cable means extending between said block and swivel means, and a double-acting hydraulic servo-motor including a reciprocatable piston and extendable piston rod means operatively interconnecting said piston and running pulley block, said servo-motor upon actuation in a direction to move the piston from a retracted toward and extended position being operative to extend said piston rod means and force said running block in the direction required to exert the downward pull upon the swivel means, and said servo-motor upon actuation to place the piston in any position other than fully extended becoming operative to decouple the running block and permit limited independent movement thereof so that the swivel means can be raised up the mast by the winch means and dropped free of any damping action that would otherwise be exerted thereon by the piston.
  2. The improved hydraulic pull-down mechanism as set forth in claim 1 in which the piston rod means is fixedly attached to the piston for reciprocal movement therewith and the running block is detached from the piston rod means.
  3. The hydraulic pull-down mechanism as set forth in claim 1 in which the piston rod means comprises two telescoping elements, one of which is attached to the piston and the other attached to the running block.
  4. The hydraulic pull-down mechanism as set forth in claim 1 in which: the hydraulic servo-motor is fastened to the mast in an upright but inverted position such that the piston rod means emerges from the bottom thereof, and the running block is positioned underneath the servo-motor with the cable means reeved from the fixed support and around the underside of the pulleys before passing upwardly to the swivel means.
  5. The hydraulic pull-down mechanism as set forth in claim 4 in which the piston rod means is fixedly attached to the piston for reciprocal movement therewith and the running block is detached from the piston rod means.
  6. The hydraulic pull-down mechanism as set forth in claim 4 in which the piston rod means comprises two telescoping elements, one of which is attached to the piston and the other attached to the running block.
  7. The hydraulic pull-down mechanism as set forth in claim 1 in which: the hydraulic servo-motor is fastened to the mast in an upright position such that the piston rod means emerges from the top thereof, the running block is located above the servo-motor, means comprising a fixed pulley block is located at the base of the mast, and the cable means is reeved from a fixed support over the pulleys of the running block thence down and underneath the pulleys of the fixed block before passing upwardly to the point of attachment to the swivel means.
  8. The hydraulic pull-down mechanism as set forth in

claim 5 in which the piston rod means is fixedly attached to the piston for reciprocal movement therewith and the running block is detached from the piston rod means.

9. The hydraulic pull-down mechanism as set forth in claim 5 in which the piston rod means comprises two telescoping elements, one of which is attached to the piston and the other attached to the running block.

10. The hydraulic pull-down mechanism as set forth in claim 5 in which a second fixed pulley block is located in the top of the nest, second cable means is attached to the running block and reeved over the second fixed pulley block, and a counterweight attached to the free end of the second cable means adapted to counterbalance the weight of the running block and first cable means so as to eliminate slack in the latter when the piston is re-

tracted and the swivel means is elevated in position for free-fall.
